TELEGRAPHIC SYSTEM.

1,395,953.

Specification of Letters Patent.

Patented Nov. 1, 1921.

Application filed January 25, 1919. Serial No. 273,142.

To all whom it may concern:

Be it known that we, ENRICO FRATTOLA, VITALE EGISTO CASTELLI, and ROMUALDO REGNONI, all three subjects of the King of Italy, and residing at 3 Via Rasella, Rome, in the Kingdom of Italy, have invented certain new and useful Improvements in Telegraphic Systems, of which the following is a specification, reference being had therein to the accompanying drawing.

This invention relates to means for protecting the instruments of a telegraphic system from the influence or disturbing effects of neighboring circuits. As an essential of the present system an alternating current of relatively high frequency is employed, so that operation may be had when condensers are used in the circuit.

In the drawings:—

Figure 1 is a view showing a simple means for the protection of the telegraphic system against outside alternating currents of low frequency.

Fig. 2 is a similar view showing an additional means of protection.

Fig. 3 is a view illustrating a protecting means similar to that of Fig. 1, superimposed on an ordinary telegraphic circuit.

Figs. 4 and 5 illustrate a means in accordance with the present invention for protecting the circuit where intermediate stations are included in series.

Figs. 6, 7, 8 and 9 indicate respectively the provision of means in a protected circuit for utilizing the vibrations of the polarized relay at the respective stations.

Fig. 10, shows a telegraphic station in accordance with the improved system arranged to act simultaneously with another ordinary telegraphic station.

In Fig. 1 there is shown a simple means for protecting telegraphic circuit against the influence of outside alternating currents of low frequency, as for example, those induced by electric traction circuits with single phase or three phase currents. In this form M represents the transmission parts, R the receiving parts, C the condensers, E the sources of the alternating current, and L the line.

The telegraphic groups are shown in shunt on the line, and the condensers maintain the circuit insulated from the earth and impermeable to continuous currents. The al-

ternating currents, both the operative and outside currents pass through the condensers and receiving parts, but such receiving parts remain inoperative to the outside currents, owing to their low frequency.

In protecting against outside currents which may reach a high value, it is contemplated that the line be grounded at various points through inductive resistances I which should be practicably impermeable to the transmission or line currents, while permitting the passage through them of large quantities of outside currents.

The simple circuit of Fig. 1 may evidently be superimposed on the conductor of an ordinary telegraphic circuit, and work simultaneously with the latter. This is illustrated in Fig. 3 wherein the circuit of Fig. 1 is shown as applied to the ordinary telegraphic circuit including the ordinary telegraphic groups T.

The receiving group consists of a polarized relay of any desired type which is connected in series with a small capacity, the whole being in shunt between the line conductor and the earth. The relative values of relay inductance and capacity in series are chosen so that for the frequency of the current employed they are nearer the resonance than the frequency of the outside currents. As an infinite number of couples of these values meet the desired result, it is possible to choose for each particular case that one which affords the necessary obstruction to the low frequency outside currents.

Therefore the new system will thus reduce to any desired extent the value of the outside currents in the receiving arrangement. When intermediate stations are to be included in series instead of in shunt, the inductance and the effective resistance of the relay should be suitably reduced and the condensers provided only in the terminal stations. The series arrangement of these intermediate stations is illustrated in Figs. 4 and 5, from which it will be seen that the current sent out from one station causes the armature of the polarized relay at the other stations to vibrate and control the circuit of a local battery, thereby govern the working of a telegraphic instrument with or without an intermediate relay. This result may be gained in the several ways indicated respectively in Figs. 6, 7, 8 and 9. In Fig. 6 the

vibration of the armature of the polarized relay closes a local circuit at intervals, which circuit is of low self induction and includes a battery P_1 , and a second relay 5 R_2 , constructed so as to keep the circuit of the instrument continually closed during the time that the battery supplies intermittent current.

In Fig. 7 the armature vibrations of the polarized relay renders intermittent a contact which when at rest is closed. The lack of continuity in this contact amounts to an increase of its resistance, and this produces the working of the instrument which has a differential winding, as indicated at A. In Fig. 8 the instrument is connected to divide the current into two circuit loops, each of which includes an inductive resistance. These resistances are such that there is ordinarily no differences of potential between the points of connection and the instrument. In the vibration of the armature of the polarized relay however the resistance of one of the loops is increased, and the instrument 20 records the signal.

In Fig. 9 the cores or armatures of the electromagnet of the instrument are polarized so that the armature would normally be attractive. The current supplied by the battery P to the circuit holds the armature 30 open, so that the recording apparatus A will register each time the current is interrupted or when the current resistance is increased. Obviously, in lieu of polarizing the instrument a second polarized relay may be placed 35 so as to close the circuit of the instrument.

Fig. 10 shows the completed construction for a telegraphic station of the present system, to act simultaneously with an ordinary 40 telegraphic station. A telegraphic machine is controlled by the polarized relay and an intermediate common relay. The transmission group comprises an ordinary vi-

brator induction coil and transmission may be effected by a five contact key.

45

The transmission group comprises a source of alternating current of the desired value and frequency, and having in series therewith a condenser of suitable capacity, which is also in correspondence with the 50 electric constants of the circuit.

What is claimed as new is:

A system adapted to telegraphic lines for receiving purposes where such lines use alternating currents of relatively high frequency and are exposed to perturbation currents from electric traction lines and the like, said system comprising in substantial resonance with the line, a polarized relay 55 of great inductance and a condenser of low 60 capacity in series with said relay, whereby there is presented a strong obstruction to perturbation currents.

In witness whereof, said ENRICO FRATTOLA has signed this specification at Rome, Italy, 65 this 21st day of December, 1918.
